UNITED STATES PATENT OFFICE.

MARIA C. SCHERER, OF BAYONNE, NEW JERSEY.

DESIGN FOR A THIMBLE.

SPECIFICATION forming part of Design No. 22,106, dated January 10, 1893.

Application filed December 15, 1892. Serial No. 455,311. Term of patent 3½ years.

To all whom it may concern:

Be it known that I, MARIA C. SCHERER, a citizen of the United States, residing at Bayonne, Hudson county, New Jersey, have invented and produced a new and original Design for Thimbles, of which the following is a specification, reference being had to the accompanying drawings, in which—

Figure 1 represents an elevation of my 10 newly designed thimble. Fig. 2 represents the rim of the thimble rolled out in a plane.

The leading feature of my design consists of a thimble upon the rim of which pigs in various attitudes are represented.

15 *a*, represents the indented top of a thimble.

b, is the rim, *c*, the flange and *d*, a cutter or thread pointer.

Upon the rim *b*, is represented a series of upright pigs in various attitudes. Thus the pigs *e*, *f*, are seated back to back, the pigs *g*, *h*, appear to shake paws, the pig *i*, faces forward and the pig *j*, is represented in profile.

What I claim is:

The design for a thimble substantially as herein shown and described.

MARIA C. SCHERER.
